UNITED STATES PATENT OFFICE

2,606,007

HEAT EXCHANGER

Clyde S. Simpelaar, Racine, Wis., assignor to
 Modine Manufacturing Company, Racine, Wis.,
 a corporation of Wisconsin

Application October 16, 1947, Serial No. 780,251

11 Claims. (Cl. 257—245)

1

This invention relates to heat exchangers of the character employed for heat exchange between two or more gases, and its principal object is to increase the efficiency of heat exchangers of this character.

Another object is to provide a heat exchanger suitable for high pressure operation and in which there is a true counterflow of gases and having a high heat transfer capacity and low pressure drop.

Another object is to provide a heat exchanger unit devoid of projections beyond the side of the unit except for inlet and outlet connections at its ends, thereby permitting the units to be assembled into compact blocks in contact with each other and thereby preventing convection currents around the individual units and securing a minimum bulk and exposed surfaces for banks of units.

Another object is to eliminate the possibility of pass to pass leakage except possibly for small areas within the connections.

Another object is to provide novel means for making a permanent connection which functions during the bonding operation to draw the connections tightly to the end bars.

Another object is to eliminate the need for separate casings for either gas.

Another object is to provide a heat exchanger for efficiently handling two or more gases.

Another object is to provide a simple mechanical assembly of relatively few individual parts, essentially self-locating and supporting in which the baking of the assembled unit completes the fabrication thereof in a single operation.

Another object is to provide a heat exchanger of which the component parts, except the inlet and outlet connections and border frame members, are fabricated from relatively inexpensive sheet or strip stock.

Another object is to provide inlet and outlet connections so disposed that they adapt themselves to simple manifolding means for an assembly of several banks of units.

Another object is to provide plenum sections at each end of the passes which also serve as useful supplemental heat transfer surfaces.

Another object is to provide a heat exchanger assembly constructed of a plurality of similar units capable of efficient usage in gas separation plants such as oxygen and nitrogen plants.

With these and other objects and advantages in view this invention consists in the several novel features of construction, arrangement and combination of parts hereinafter fully set forth and

2

more particularly defined in the appended claims.

The invention is clearly illustrated in the drawings accompanying this specification, in which:

Fig. 1 is a diagrammatic perspective view of a heat exchanger assembly employing several banks of units embodying a simple form of the present invention and illustrating manifolding therefor;

Fig. 2 is a side elevation broken out and partly broken away of a heat exchanger embodying a simple form of the present invention;

Fig. 3 is a diagrammatic view in end elevation of three units of the heat exchanger set side by side;

Fig. 4 is a side elevation of one of the units partly broken out and partly broken away and illustrating certain heat transfer members contained within the unit;

Fig. 5 is an end elevation of the unit seen in Fig. 4, with a pull-out sheet and a fragment of a separating sheet shown therebelow;

Fig. 6 is an under plan view partly broken out of the unit illustrated in Fig. 4;

Fig. 7 is a horizontal section taken on the line 7—7 of Fig. 4;

Fig. 8 is a vertical section taken substantially along the line 8—8 of Fig. 4;

Fig. 9 is a perspective view of certain border frame members of the device;

Fig. 10 is a perspective view illustrating the connection between one of said border frame members and an inlet or outlet connection;

Fig. 11 is a perspective view of a modified form of said connection;

Fig. 12 is a perspective view of a certain baffle;

Fig. 13 is a plan view partly broken away of a side plate seen in Fig. 4;

Fig. 14 is a fragmental perspective view of a certain plenum section;

Fig. 15 is a greatly enlarged detail fragmental vertical cross section illustrating certain heat transfer fins and channel members of certain border frame members;

Fig. 16 is an under plan view of a fragment of one of the fins seen in Fig. 15;

Fig. 17 is a fragmental vertical section taken on the line 17—17 of Fig. 15;

Fig. 18 is a fragmental perspective view of one of the fins seen in Figs. 15 and 17 inclusive; and

Fig. 19 is a diagrammatic view illustrating the method of assembling the border frame members with the inlet and outlet connections.

Referring to said drawings and first to Figs. 1 to 3 inclusive, the reference characters 20 designate several of the present heat exchanger units

with their broad sides placed side by side and arranged in banks, and provided at their ends with inlet and outlet manifolds which will be described later on in this specification.

The heat exchanger units are substantially identical in construction and each comprises a fabricated elongated rectangular unit composed of alternate slabs of longitudinally extending nested together fin elements 21 (see Figs. 4, 7, and 15 to 18 inclusive), which provide passes for gas of one temperature, and intermediate rows of lengthwise extending nested together fin elements 21^a providing passes for a gas of a different temperature. The slabs of fin elements are arranged in heat exchange relation with respect to each other. The slabs of fin elements extend lengthwise of the unit from top to bottom thereof as viewed in Figs. 4 and 5, and may be separated by thin metal sheets 22 and may have side sheets 23 applied to their outer side faces. The fin elements may be channel shaped, as seen in Figs. 15 and 18.

The fin elements shown are formed from very light gage metal about .004 of an inch thickness, and are made into channel form arranged to be together. The cross wall 24 of each fin element is slit from side to side to provide alternate and intermediate strip fins 24^a, 24^b, and the intermediate strips 24^a formed by the slits are struck up into the channel of the fin element, thereby providing strip fins lying in two planes. To prevent the fin elements from overnesting, shoulders 26 are provided on the side walls, which shoulders project inwardly therefrom to form widened seats or stops for the next adjacent fin element to bear against. The shoulders of adjacent fin members are offset with respect to each other, so that the shoulders, at least in part, bear against the unshouldered portion of the adjacent fin element. The shoulders are formed by providing wider fin strips 24^c at spaced places along the length of the fin elements and slitting the wider fin strips each at two places at the corners of the fin element and striking up the metal between said slits so as to bend the material inwardly and then transversely toward and to the wider fin strip. As a preference, the side walls of the fin element are offset outwardly as at 25^a, a distance equal to the thickness of the material, whereby the fin elements may nest together with the one fin element seated against the shoulders of the next adjacent fin element, and providing true vertical edge surfaces.

Certain of the strip fins may be struck up out of the plane of the other strip fins, whereby the contact of gas is discontinuous instead of continuous as would be the case if the cross walls were made intact. Furthermore, the gaps at the edges of the strip fins permit the gas to flow laterally from each channel to the next adjacent one thereabove or therebelow.

Extending from both ends of the slabs of fin elements are plenum sections 27 preferably composed of corrugated sheets (see also Fig. 14) folded into longitudinally extending oppositely directed channels through which the gas may flow to or from the fin elements as the case may be, and the upper and lower walls of the channels are formed with openings 28, whereby the gas may flow laterally from one channel to the other as well as lengthwise through the channels. Like the fin elements, the plenum sections extend from top to bottom of the unit.

The plenum sections or corrugated sheets are provided to resist the high pressures to which a

heat exchanger of this character is subjected; they also act in the nature of heat conducting fin members. The fin elements and corrugated sheets provide passes or passages for the gas to flow through from one end of the unit to the other, as seen by the dotted lines in Fig. 2.

Surrounding the fin elements are alternate and intermediate border frame members 29 (see also Figs. 4, 5 and 9), each compression of two L-shaped sections 30, 30, the long arms 32 of which extend at right angles to the main arms 34 of the L-shaped sections. Each main arm 34 has also a short arm 33 paralleling the arm 32 and projecting in the same direction from the arm 34. The end of the arm 32 of each section and the end of the short arm 33 of the other section are spaced apart to leave gaps (see Fig. 4) between them through which gas may enter or leave the plenum sections whose outer ends are not covered by the long arms 32.

The intermediate border frame members are inverted with respect to the alternate ones so as to bring the gaps of the intermediate border frame members adjacent to the long arm of the alternate border frame members. In Fig. 5, the upper end shows alternate plenum sections blocked by the long arms 32 of the upper border frame members 30, and the lower end shows the intermediate plenum sections blocked by the long arms 32 of the lower border frame members 30. These border frame members bear against the edges of the slabs of fin elements and against the top and bottom edges and the ends of the plenum sections.

The arms 32, 33 are formed with outwardly directed lugs or ears 35 which extend through notches 37 in the flanges 36 of the inlet and outlet connections 40, 40^a, 41, 41^a and are apertured to receive pins 37' which project from both sides of the lugs or ears 35 and stout springs 38 are interposed between the flanges 36 and the pins 37' and function to draw the inlet and outlet connections tightly against the arms 32, 33 of the border frame members during fabrication of the unit. The springs have inclined arms that bear against the flanges and are connected to saddle portions that engage the pins. Each spring is U-shaped as seen in Fig. 10, the two arms thereof being connected by a cross section 39. Each spring can be readily slipped into place between the flange and pin.

As an alternate method of fastening the border frame members to the inlet and outlet connections, the ears or lugs 35^a may be provided with enlarged heads 35^b and the U-shaped springs 38^a may engage between the flanges 36 and shoulders 35^c of the heads. Instead of the saddle shown in Fig. 10, the springs may have flat portions engaging the shoulders.

Each inlet and outlet connection is formed with a hollow block 42 which connects and projects laterally from each pair of flanges 36 and terminates in a flange 42^a formed with perforated ears 43 to which a header pipe may be secured. The flange 42^a is preferably cylindrical and the inner face of the block 42 flares outwardly toward the side faces of the block as seen in Fig. 7.

There is an inlet connection 40 or 41 on each end of the unit, one for admitting gas to the alternate stacks of passes and the other one for admitting gas of a different temperature to the intermediate stacks of passes, and there is an outlet connection 40^a or 41^a on each end of the unit through which the gases discharge from the

unit. All of the inlet and outlet connections are of similar construction. In the form of the invention illustrated, the inlet connection for one gas is disposed opposite the inlet connection for the other gas. Where the inlet connection is located adjacent the lower side of the unit, the outlet connection therefor is located adjacent the upper side of the unit, whereby the gas may flow through the entire unit from inlet to outlet. As a result, the gas flowing in through the inlet connection flows along the passes and also laterally with respect to them toward the other end of the unit (assuming that in practice the unit is set edgewise as indicated in Fig. 1), and discharges through the upper outlet connection of the top and bottom row of units, and the other gas flowing in through the other lower inlet connection flows along the intermediate passes and also laterally toward the top of the unit and discharges through the upper outlet connection. With the inlet and outlet connections located as above explained a true counter-flow of the respective gases is obtained.

As has been explained, the two sections of each border frame member provide gaps between their ends through which gas may flow from an inlet connection to the passes that are aligned with said border frame members and, like the passes, the border frame members are arranged in alternate and intermediate relationship, and adjacent border frame members stand reversely with respect to each other (see Fig. 9), that is to say, if the gaps register with the inlet and outlet connections for one stack of passes, the gaps of the next adjacent border frame member register with the inlet and outlet connections for the next adjacent passes and the long bars of this border frame member extend across the ends of the first mentioned passes, thereby preventing gas from entering or leaving the intermediate passes at that end of the unit. As a result, gas of one temperature flows through alternate passes and gas of a different temperature flows through the intermediate passes.

The L-shaped border frame sections are of similar construction; as shown, each section (see Fig. 9) comprises a main bar 34 which is composed of a channel shaped member 34^a in one end of which is rigidly secured the right angle member 32^a of the long bar 32 which extends along the ends of certain passes, and rigidly secured in the other end of the channel shaped member 34^a is a right angle block 33^a which forms a short bar 33 of the border frame section. The channel shaped members are let into rabbeted portions formed in the long bar and block in order that the side faces of the channel shaped members and long bar and block may be flush. If desired, the long bars may be formed with apertured lugs 45 slightly wider than the border frame members, whereby when the parts are assembled and bonded together the lugs will contact with each other and form one long apertured lug which may be used for lifting purposes.

A simple means for securing the channel members 34 to the bars 32 and blocks 33 is provided by drilling holes 46 in the parts 32^a, 33^a (see Figs. 6 and 8) and indenting the material of the channel members into the holes as seen at 47. In the completed unit, the channel members, bars and blocks are bonded together.

To provide reenforcement means between the sheets 22 at the gaps between the border frame sections, corrugated strips 48 of the same width

as the border frame members and of the same height as the height of the opening in the inlet or outlet connection may be inserted into said gaps.

5 Inasmuch as the outermost stacks of fin elements have surface contact with only one adjacent stack of fin elements, whereas, the other stacks of fin elements have surface contact with a stack of fin elements on each side thereof, it has been found desirable to restrict the flow of gas through the outermost passes as by providing baffles 49 (see Fig. 12) on the corrugated strips 48^a, which correspond in location with the corrugated strips 48. The baffles 49 narrow up the space through the convolutions of the corrugated strips, thereby reducing the amount of gas which may flow through the outermost passes, to achieve uniform heat transfer through each pass. Another simple means for accomplishing the same result is to make the fin elements of the outermost passes half as wide as the others. A further means would be to incorporate a restriction in the outermost passes by means of a projecting boss on the connection, or by using a special form of plenum section which would restrict the flow to give desired thermal balance. To enable individual units to be slid out of a bank of units, sliding pads 65 (see Figs. 2, 5 and 8) may be secured to the lower side of the units, and a continuous large sheet 66 or several large sheets are placed between the several banks of units and a pull-out sheet 66^a one for each unit may be laid upon the large sheet below for the sliding pads to rest upon. To withdraw any unit, the pull-out sheet therebelow is withdrawn and the unit then rests on the large sheet. It may then be readily withdrawn. The manifolds are, of course, uncoupled from the units.

In constructing a unit as above described, an outermost sheet 23 is first laid in place on a horizontal support. The sheet 23 is as long and wide as the unit and is formed with extensions 23^a (see Fig. 13) which underlie the blocks 42 of the inlet and outlet connections. To hold the inlet and outlet connections in place on the sheet, rivets 50 are inserted upward through holes 23^b in the sheet 23 and into holes 51 in the blocks 42.

One of the border frame sections 30 is then laid on the sheet in an oblique direction with respect to the length of the sheet as seen in Fig. 19, and the ear or lug 35, adjacent the corner of the section, is inserted into the lowermost notch in the flange 30 of the adjacent connection. The section is then swung into place, the ear or lug in the short arm 33 entering the notch in the lowermost flange 36 of the oppositely disposed connection, the intermediate ear or lug 35 on the bar 32 entering the opposite notch in the other flange 36 of the first mentioned connection, and the ear or lug 35 at the end of the long bar 32 entering the lowermost notch in an adjacent flange 36 of the connection which is diagonally opposite the short arm 33. The pins 37 are then inserted into the holes in the ears or lugs of the section which has been laid in place, and the springs 38 inserted between the flanges 36 and pins 37, thereby drawing the border frame section tightly against the connections.

The companion border frame section 30 is then put in place in the same manner except that the fulcrum point on which the border section is swung is diagonally opposite the fulcrum point of the first section.

As will be readily understood a complete

border frame member having two diagonally opposite gaps, and two diagonally opposite long bars that extend across the inner sides of two connections will result therefrom.

The fin elements are then put in place in nested condition from side to side of the main bars of the border frame members, after which the plenum sections or apertured corrugated sheets 27 are put into place between the ends of the fin elements and the connections. A sheet 22 preferably of less thickness than the outermost sheet 23 is laid in place on the assembly, and the second set of border frame members is put in place as before, except that they are reversed with respect to the first set so that the gaps will be reversely located with respect to the gaps of the first laid border frame members.

In like manner, course after course is laid until the other ends of the flanges of the connections are reached and an endmost sheet 23 is then laid on the assembly and held in place by rivets 50 as was the other outermost sheet 23.

The edge portions of the sheets 22, 23 and flanges of the channel shaped border frame members 34 may be deformed as at 66 (see Fig. 6) by a suitable tool, whereby to temporarily lock the sheets and channel shaped members 34 together.

It is to be understood that the surfaces of the various members entering into the assembly are coated with bonding material, or where practical thin sheets of bonding materials may be used between the members of the assembly. This is shown in exaggerated form at 60 in Fig. 15.

The assembly is now baked in a suitable baking oven, thereby fusing the bonding material and bonding the several members of the assembly together. It will be noted that as the bonding material between the inlet and outlet connections and the border frame members melts, the stout springs 38 become coated with the bonding material and continue to press the connections and bars together, whereby they are firmly bonded together to provide an integral unit reenforced by the coated springs.

For handling large volumes of gases, several banks of the units set side by side may be used with the inlet and outlet connections connected to suitable inlet and outlet manifolds. In Fig. 1 are shown several stacks of units set side by side. An inlet manifold 52 and an outlet manifold 53 are provided at each end of the units. In the arrangement shown, the inlet manifold has two branches 54 which are connected to adjacent inlet connections by pipe connections 55. The inlet manifold at the other end of the assembly is connected to the adjacent inlet connections at the other end of the assembly in the same manner. The outlet manifolds 53 each have two branches 56 connected to the outlet connections of the units by pipe connections 57. It is to be noted that, as shown, the units 20 of the middle row are inverted, bringing the inlet connections toward the upper sides of the units.

Inasmuch as the passes are separated from each other by metal sheets, there is no likelihood of leakage between the passes. Any leakage in the small areas within the connections can be readily detected and stopped.

If desired, the several units of each row may be tied together by a tie rod 58 (see Fig. 3) which extends through the apertured lugs 45 and is provided with a coiled compression spring 59 between an end unit 20 and a nut 60 threaded

on the tie rod. The other end of the tie rod may be provided with a head 61 to bear against the other end unit. In this case, the lugs 45 may be made slightly narrower than the units, and washers 62 may be inserted between adjacent lugs.

In the operation of the heat exchanger, gas of one temperature is forced through the alternate passes from inlet to outlet and a gas of a higher or lower temperature is forced through the intermediate passes from inlet to outlet.

Heat from the hotter gas is conducted to the fin elements through which it flows, and from said fin elements the heat is conducted to the 15 fin elements through which the cooler gas is flowing and the heat is absorbed by the cooler gas.

The gas in flowing through the passes, flows longitudinally therethrough and also laterally 20 through the holes in the plenum sections and through the gaps between the fin strips of the fin elements. Consequently, gas entering at the bottom of a unit discharges at the top thereof.

While I have shown and described the heat 25 exchanger assembly as extending in a horizontal direction this is not necessary as it may extend vertically and operate in the same manner as if placed horizontally.

Having thus described my invention, it is obvious that various immaterial modifications may 30 be made in the same without departing from the spirit of my invention; hence, I do not wish to be understood as limiting myself to the exact form, construction, arrangement and combination 35 of parts herein shown and described or uses mentioned.

What I claim as new and desire to secure by Letters Patent is:

1. In a heat exchanger for high pressure applications, alternate and intermediate slabs of fin elements arranged in heat transfer relation, the fin elements of each slab being in communication with each other, two sets of inlet and outlet connections, one set communicating with the alternate slabs of fin elements and one set 40 communicating with the intermediate slabs of fin elements, border frame members surrounding said fin elements and having ports connecting one set of inlet and outlet connections with the alternate slabs of fin elements and other ports connecting the other set of inlet and outlet connections with the intermediate slabs of fin elements, each connection having an inner face 45 abutting the adjacent face of the exchanger, and individual means interlocking each connection with each adjacent border frame member, said fin elements, border frame members, connections, and interlocking means being bonded into an integral structure.

2. In a heat exchanger, alternate and intermediate slabs of interlocked fin elements arranged in heat transfer relation to each other and having oppositely disposed overlapping portions, metal sheets extending substantially parallel with 50 and interposed between the adjacent overlapping portions of respective alternate and intermediate fin elements, two sets of inlet and outlet connections, one set communicating with the alternate slabs of fin elements and one set communicating with the intermediate slabs of fin elements, alternate and intermediate border frame members partially surrounding the slabs of fin elements, said border members, fin elements, sheets, and connections being bonded together

70 75 to form a single integral structure, the alternate

border frame members having gaps therein forming ports between one set of inlet and outlet connections and the alternate fin elements, and the intermediate border frame members having gaps therein forming ports between the other set of inlet and outlet connections and the intermediate fin elements.

3. In a heat exchanger, alternate and intermediate slabs of interlocked channel shaped fin elements each having spaced transversely extending strip fins and arranged in heat transfer relation to each other, two sets of inlet and outlet connections, one set communicating with the alternate slabs of fin elements and one set communicating with the intermediate slabs of fin elements, alternate and intermediate border frame members partially surrounding the slabs of fin elements, the alternate border frame members having gaps therein forming ports between one set of inlet and outlet connections and the alternate fin elements, and the intermediate border frame members having gaps therein forming ports between the other set of inlet and outlet connections and the intermediate fin elements, all of said elements being bonded together to form a single integral structure.

4. In a heat exchanger, alternate and intermediate slabs of interlocked channel shaped fin elements each having transversely extending strip fins arranged in two planes, said fin elements being arranged in heat transfer relation to each other, two sets of inlet and outlet connections, one set communicating with the alternate slabs of fin elements and one set communicating with the intermediate slabs of fin elements, alternate and intermediate border frame members partially surrounding the slabs of fin elements, the alternate border frame members having gaps therein forming ports between one set of inlet and outlet connections and the alternate fin elements, and the intermediate border frame members having gaps therein forming ports between the other set of inlet and outlet connections and the intermediate fin elements, all of said elements being bonded together to form a single integral structure.

5. A heat exchanger comprising alternate and intermediate slabs of interlocked channel shaped fin elements, two sets of inlet and outlet connections, one set for the alternate fin elements and one set for the intermediate ones, alternate and intermediate L-shaped border frame members surrounding the slabs of fin elements and secured to the connections, there being gaps between the sections of the alternate border frame members through which fluid may flow to and from alternate slabs of fin members, and said intermediate border frame members having bars blocking the entrance to the intermediate fin elements, said connections each abutting the adjacent bars, said fin elements, frame members, and connections all being bonded together to form a single integral structure.

6. A heat exchanger comprising alternate and intermediate slabs of interlocked channel shaped fin elements, separating sheets interposed between each pair of adjacent slabs, and a cover sheet for each outer slab, two sets of inlet and outlet connections, one set for the alternate fin elements and one set for the intermediate ones, border frame members positioned between the respective sheets and surrounding each of the slabs of fin elements and secured to the connections, there being gaps between the sections of the border frame members through which fluid

may flow to and from alternate slabs of fin members, and the intermediate slabs of fin members being closed to said set of inlet and outlet connections but in open communication with the other set of inlet and outlet connections, all of said elements being bonded together into a single unit with the respective frame members forming the side walls of the respective slabs whereby the joints between said sheets and each of said frame members extend to the exterior of the exchanger.

7. In a heat exchanger, a plurality of slabs of passes arranged in heat transfer relation to each other, border frame members having gaps therein for corresponding slabs of passes, and sets of inlet and outlet connections abutting said frame members at said gaps, and means interlocking the respective connections with each of the adjacent frame members, all of said elements being bonded into a single integral structure.

8. In a heat exchanger, the combination of a plurality of fabricated slabs of longitudinally extending, interlocked fin elements arranged one upon the other, a separator sheet interposed between each respective pair of adjacent slabs, a cover sheet for each of the two outer slabs, individual border frame members for each slab positioned between adjacent sheets and forming the outer side walls of the exchanger, the latter having an inlet and outlet therein respectively communicating with a plurality of spaced slabs and providing means for the entry and exit of fluid through said slabs, said exchanger having a second inlet and a second outlet therein respectively communicating with other of said slabs adjacent to and in heat transfer relation with the first group of slabs, each group of slabs being blocked adjacent the inlet and outlet of the other group of slabs, all of said elements being bonded together to form a single integral structure with the joints between said sheets and frame members extending to the exterior of the exchanger.

9. In a heat exchanger, the combination of a plurality of elongated relatively thin slabs of longitudinally extending, interlocked fin elements, each slab constituting a fluid pass, a separator sheet interposed between each respective pair of adjacent slabs, a cover sheet for each of the respective outer slabs, said sheets being longer and wider than said slabs to extend beyond the ends and sides of the latter, a pair of plenum sections for each slab respectively disposed between the adjacent sheets at opposite ends of the respective slabs, the height of each plenum section being substantially equal to the thickness of its associated slab, individual border frame members for each slab positioned between the sheets adjacent the latter and adapted to operatively enclose such slab and its associated plenum sections, said exchanger having a fluid inlet and a fluid outlet therein respectively communicating with the plenum sections of a plurality of spaced slabs to provide means for the entry and exit of fluid through said slabs, said exchanger having a second fluid inlet and a second fluid outlet therein respectively communicating with the plenum sections of other of said slabs adjacent to and in heat transfer relation with the first group of slabs, the plenum sections of each group of slabs being blocked adjacent the inlets and outlets of the other group of slabs, each plenum section having a plurality of openings therein whereby the respective inlet or outlet associated therewith operatively communicates with the entire end of the respective slab,

11

all of said elements being bonded together to form a single integral structure.

10. In a fluid pass for heat exchangers comprising alternate and intermediate slabs of fin elements, each of said slabs comprising the combination of a plurality of fin elements, each comprising an elongated strip of relatively thin metal longitudinally folded along spaced, parallel lines to form a channel-shaped structure having oppositely disposed co-extensive side walls extending in substantially parallel planes, each side wall being offset outwardly intermediate its edges, approximately the thickness of the material employed, to provide longitudinally extending edge portions positioned in substantially parallel planes, between which a like, similarly positioned fin element may be inserted, the intermediate wall connecting said side walls having a plurality of substantially uniformly spaced, parallel slits therein extending substantially from one side wall to the other to form a plurality of individual strip fins, each fin extending from side wall to side wall, alternate fins being deformed at their junctures with the side walls out of the plane of the other fins, with all of said alternate fins substantially lying in a common plane extending parallel to the plane of said other fins, and means formed from the side walls at spaced points therealong extending inwardly to form the said offsets providing shoulders aligned with said offsets upon which a like fin element may seat to maintain the fins of the latter in spaced relation with the fins of the former, said fin elements being assembled in interlocked relation, with each succeeding fin element having portions of its side walls intermediate the fins associated therewith and the offsets positioned between the offset portions of the preceding fin element to form an internally finned slab, means for operatively closing the open ends of the slab thus formed, metal sheets overlying the top and bottom of the latter and said closure means, and inlet and outlet means associated with said alternate and intermediate slabs and communicating with the ends of the latter, said fin elements, closure means, sheets and inlet and outlet means being bonded into an integral unit.

11. In a fluid pass for heat exchangers comprising alternate and intermediate slabs of fin elements, each of said slabs comprising the combination of a plurality of fin elements, each comprising an elongated strip of relatively thin metal longitudinally folded along spaced, parallel lines to form a channel-shaped structure having oppositely disposed co-extensive side walls extending in substantially parallel planes, each side wall being offset outwardly intermediate its edges, ap-

12

proximately the thickness of the material employed, to provide longitudinally extending edge portions positioned in substantially parallel planes, between which a like, similarly positioned fin element may be inserted, the intermediate wall connecting said side walls having a plurality of spaced, substantially parallel slits therein extending substantially from one side wall to the other to form a plurality of individual strip fins, each fin extending from side wall to side wall, certain of said fins being deformed at their junctures with the side walls out of the plane of the other fins, with all of said fins substantially lying in parallel planes, said fin elements being assembled in interlocked relation, with each succeeding fin element having portions of its side walls intermediate the fins associated therewith and the offsets positioned between the offset portions of the preceding fin element to form an internally finned slab, means for operatively closing the open ends of the slab thus formed, metal sheets overlying the top and bottom of the latter and said closure means, and inlet and outlet means associated with said alternate and intermediate slabs and communicating with the ends of the latter, said fin elements, closure means, sheets and inlet and outlet means being bonded into an integral unit.

CLYDE S. SIMPELAAR.
